MANUFACTURE OF THREAD

Paul Edward Harrison, Donelson, Tenn., assignor
to Du Pont Rayon Company, New York, N. Y.,
a corporation of Delaware

Application October 13, 1932, Serial No. 637,604

6 Claims. (Cl. 18—8)

This invention relates to the manufacture of thread. The invention also relates to hollow spindle motors. More particularly the invention relates to the manufacture of regenerated cellulose thread by the bucket process and will be described in its relation to that process, although it is equally applicable to any process wherein thread is gathered or treated in a revolving bucket.

10 In the manufacture of rayon by the bucket process the prior art discloses the projection of a viscose solution through fine orifices into a setting bath, the withdrawal of the thread from the bath by a wheel, which in the industry is called 15 a godet wheel, the passing of the thread through a funnel into a bucket revolving at high speed, and the reciprocation of the funnel to lay the thread against the wall of the bucket, or against the other layers of thread, in the form of superimposed helices. So far as I know, in the prior 20 art the spinning machines have involved thread guides suspended over the tops of the buckets on a framework which is moved up and down by mechanical linkages and gearing. Those apparatus have been in the way, have caused the loss of considerable time in doffing cakes since 25 these mechanisms must be moved before the cake can be taken from the bucket and since they must be replaced before the threads can again 30 be introduced into the bucket, have been cumbersome, expensive of power, without ability to operate satisfactorily at high speed, and expensive of funnel guides. Attempts have been made to improve these bucket spinning and 35 bucket cake treating machines of the prior art, but without considerable success.

It is an object of this invention to provide a means and method of making thread. Another object of this invention is to provide a new means 40 and method of spinning and treating bucket cakes. Another object of the invention is to provide a new machine which has a variety of uses. Other objects of the invention will be in part apparent and in part set forth elsewhere 45 herein.

These objects are accomplished, generally speaking, by bringing the rayon into the spinning bucket through the bottom thereof, by the use of a hollow armatured motor, and by the means, method, and details of construction herein set forth and claimed.

In the drawings, Figure 1 is an elevational view, partly in section, of a preferred embodiment of my invention; Figure 2 is an elevational 55 view, partly in section, of a modified form of

my invention; Figure 3 shows a hose connection for attachment to element 42 or 114 through which liquids may be introduced into the interior of the bucket for the purpose of washing or treating a completed bucket cake.

In Figure 1, 10 indicates a candle filter through which a viscose solution is passed before regeneration; 11 indicates the spinnerette through the fine orifices of which the viscose solution is passed into the setting bath; 12 indicates the tank containing the setting bath; 13 indicates a lining of lead or of other suitable material capable of resisting the corrosive action of the fluids of the setting bath; 14 indicates the thread; 15 indicates a godet wheel over which the thread 15 is passed two or three times before being fed to the reciprocating mechanism and the bucket; 16 indicates a shaft on which the godet wheel is mounted; 20 is an electric motor of any satisfactory electrical type having an armature, not 20 shown; 21 is the core of the armature which is made hollow; 211 is an extension on the end of armature core 21; 30 is a bucket mounted on the extension 211; 40 is a rack; 41 is a support on 25 said rack; 42 is a means for holding a funnel mounted in support 41; 43 is a guard of bakelite or other material designed to protect the stem of the funnel; 44 is a funnel for reciprocating the thread in the bucket; 45 is a gear segment in mesh with rack 40; 46 is a reciprocable shaft 30 upon which the gear segment is mounted; 50 and 51 are drain pipes for collecting the drip from 35 the godet wheel and the fluid ejected by the revolving bucket, respectively.

The operation of my invention is as follows: 35

A viscose solution is extruded from the spinnerette 11 into a setting bath; is withdrawn from the setting bath, and passed around the godet wheel 15. By the assistance of a blast of air or of a stream of water the operator forces the end 40 of the thread leaving the godet wheel into funnel 44 and through it into the revolving bucket. The funnel 44 passes through the hollow armature 45 of the motor and is protected against breakage by the guard 43 which also passes into the hollow armature of the motor without touching it. As the bucket revolves the thread is drawn into the bucket at a rate controlled by the godet wheel. The shaft 46 reciprocates the gear 45, which in 50 turn reciprocates the rack 40 and the reciprocating funnel 44. As the funnel 44 reciprocates, the thread is laid helically in the bucket and builds up into a hollow cake whose height is controlled by the range of the funnel's reciprocation. Any 55

suitable type of bucket cover may be used if a bucket cover is desired.

In Figure 2 is shown a modified form of the invention. In this figure, 100 is a bucket well; 101 is a bearing in the bucket well; 102 is a plate mounted for rotation on said bearing; 103 is a bucket fitting plate 102 and resting thereon; 104 is a bearing in the bottom of the bucket; 105 is a safety cover placed over the bucket chamber; 106 is a reciprocating bar; 111 is a support depending from said bar; 112 is an electric motor attached to said support 111; 113 is the hollow core of the armature of said motor which is splined to the bearing 104 of the bucket so that the core 113, as it rotates, will rotate the bucket but will be capable of sliding movement relative thereto; 114 is an adjustable funnel holder; 115 is a funnel held thereby and passing through the hollow core of the motor armature into the bucket; 106 is an adjustable nut in the safety cover 105 designed to prevent the bucket 103 from lifting out of position on plate 102 during the reciprocation of the core 113.

The mechanism described in Figure 2 operates as follows:

A reciprocating mechanism, not shown, which may be of prior art type, moves the motor and the funnel to and fro axially of the bucket. As the motor armature revolves, it revolves the bucket regardless of the position of the motor with respect to the bucket because of the spline which permits this relative movement. After the spinning has been completed, the motor is stopped; the sleeve 113 is withdrawn from the bucket head and from the cover 105 by lifting the member 110, the cover 105 is then moved out of the way, the bucket is taken out of the bucket well, the cake is doffed, and the bucket is returned to place for further service. If it is desired the end 40 of the armature core opposite the bucket can be extended and counterweighted to balance the weight of the bucket.

In the functioning of the form of the invention shown in Figure 1, a number of machines will be mounted side by side, their godet wheels and reciprocating gear sectors being mounted on a shaft extending the length of the set-up. The drainage from all machines will pass to a single pipe and to a common reservoir.

50 My invention eliminates the complicated and cumbersome reciprocating mechanisms heretofore used in spinning machines. It reduces the power requirements needed for the operation of the reciprocation mechanism. It makes the removal of a bucket during the doffing of the cake unnecessary when the form of the invention shown in Figure 1 is used. It saves space and makes it possible to mount spinning machines in tiers. Other advantages of the invention are apparent.

60 As many apparently widely different embodiments of this invention may be made without de-

parting from the spirit and scope thereof, it is to be understood that I do not limit myself to the specific embodiments thereof except as defined in the appended claims.

I claim:

1. In a machine for making thread, an electric motor provided with a revolvable armature having a hollow core, an extension on said core, a bucket fixed to said extension, a reciprocable pinion, a rack in mesh therewith, a support on said rack, a traversing funnel adjustably carried by said support extending through said hollow core into the bucket, means for feeding thread to said traversing funnel, means for reciprocating the rack and pinion, means for collecting liquid thrown out by the bucket, and means for collecting liquid dropped by said feeding means.

10 2. In a machine for making thread, an electric motor provided with a revolvable armature having a hollow core, an extension on said core, a bucket fixed to said extension, a reciprocable pinion, a rack in mesh therewith, a support on said rack, a traversing funnel adjustably carried by said support extending through said hollow core into the bucket, means for feeding thread to said traversing funnel, and means for reciprocating the rack and funnel.

20 3. In a machine for making thread, an electric motor provided with a revolvable armature having a hollow core, an extension on said core, a bucket fixed to said extension, a reciprocable pinion, a rack in mesh therewith, a support on said rack, a traversing funnel adjustably carried by said support extending through said hollow core into the bucket, means for feeding thread to said traversing funnel, and means for reciprocating the rack.

30 4. In a machine for making thread, an electric motor provided with a revolvable armature having a hollow core, an extension on said core, a bucket fixed to said extension, a reciprocable support, a traversing funnel adjustably carried by said support extending through said hollow core into the bucket, means for feeding thread to said traversing funnel, and means for reciprocating the support.

40 5. In a machine for making thread, an electric motor provided with an armature having a hollow core, an extension on said core, a bucket fixed to said extension, a reciprocable traversing funnel extending through said hollow core into the bucket, means for feeding thread to said traversing funnel, and means for reciprocating the traversing funnel.

50 6. In a machine for making thread, a motor provided with a hollow core, an extension on said core, a bucket fixed to said extension, a reciprocable traversing funnel extending through said hollow core into the bucket, means for feeding thread to said traversing funnel, and means for reciprocating the traversing funnel.

60 PAUL EDWARD HARRISON.
